UNITED STATES PATENT OFFICE

ASHTON G. STEVENSON, OF CHICAGO, ILLINOIS

MEANS AND METHOD FOR MAKING PRINTERS' METAL FURNITURE

Application filed October 8, 1928. Serial No. 311,183.

My invention relates to printers' metal furniture and means and methods of producing same.

This present invention is an improvement on the invention of a slug or furniture mold as disclosed in U. S. Patent No. 1,260,828 issued to me March 26, 1918. The mold disclosed in said patent was particularly devised for use on a lino-type or similar type casting machine for making relatively thick slugs for use as type furniture or base material and carried a core whereby such slugs were made hollow for reducing their weight and making more solid castings. Such a mold was made with parallel faces forming the top and bottom of the mold and it was discovered, in use, that the slugs cast in such molds did not have perfectly parallel side faces but were slightly thinner in thickness at their middle portions than at their ends, caused by shrinkage. Such shrinkage is more pronounced at the bottom edges of the slugs than at the tops, the tops of the slugs being substantially of uniform width throughout their length. Consequently, when these slugs were used of full or 30 em length such variation in thickness was not detrimental, but such slugs, though produced of standard 30 em length, are frequently cut to shorter lengths and if they were cut to 15 em length by being cut in two halfway between their ends, one end of the short slugs thus produced would have slightly inclined sides and would not lock up properly but would tend to cause the form to bulge up under the locking pressure.

In considering ways and means for correcting this inaccuracy which, although only a few thousandths in extent, was sufficient to cause trouble in locking up some forms, I made use of many expedients, but none were successful until I devised my present method.

My invention will be more readily understood by reference to the accompanying drawings forming part of this specification and in which:—

Fig. 1 is a perspective view of one of my improved slugs or piece of type furniture;

Fig. 2 is a front view of one of my im-

proved molds used for making my improved slug;

Fig. 3 is a fragmentary view showing a mold wheel of a lino-type machine equipped with one of my improved molds;

Fig. 4 is a top plan view of a jig used for producing the cap of my improved mold;

Fig. 5 is a vertical section on the line 5—5 of Fig. 4;

Figs. 6 and 7 are vertical cross sectional views on the lines 6—6 and 7—7, respectively, of Fig. 4;

Fig. 8 is a front elevational view of a jig used for producing the lower part of one of my improved molds;

Fig. 9 is a horizontal section on the line 9—9 of Fig. 8;

Figs. 10 and 11 are vertical, sectional views on the lines 10—10 and 11—11, respectively, of Fig. 8;

Fig. 12 is a perspective view of the cap part of the mold particularly showing the ground off portion; and

Fig. 13 is a vertical central cross-section of a mold without my improvement.

In said drawings 1 illustrates one of my improved slugs made in one of my improved molds and having parallel flat side faces 2, as shown at 3. The slug 1 is preferably made hollow on its under side and has a top flat surface 4. The side faces 2 of the slug are the sides which it has apparently been impossible to make absolutely parallel heretofore, and success has only been attained by means of my improved mold.

The dotted line 5 on Fig. 1 indicates the ordinary discrepancy, though greatly exaggerated, of a slug made in my molds before I improved them, and the dotted curved line 5' indicates the area or extent of the discrepancy.

The mold 6, as shown in Fig. 2, consists of a cap 7 and a base 8 which are substantially the same as the usual cap and base of molds for use on lino-type mold wheels 9, Fig. 3. Between the cap 6 and base 8 is arranged what is known as a liner or core 10, having its ends formed into block-like spacer parts 11 which hold the cap and base properly spaced to form a mold opening 12. In the form

shown, the liner or core has an intermediate part or bar 13 connecting the two end spacer parts and extending longitudinally through the mold opening. This is for the purpose of making the slug hollow and lighter. This bar divides the mold opening longitudinally and provides two slots 14 and 15 at the rear through one of which the metal is forced in the process of casting a slug.

10 The under side surface 16 of the cap and the top surface 17 of the base are the surfaces which produce the side faces 2 of the slug.

For the purpose of overcoming the fault or detriment of the slug being thinner at its rear middle portion than at its ends, as indicated in Fig. 1 by the dotted lines 5—5, I so form the bottom surface 16 of the cap and the top surface 17 of the base that when assembled for use the mold space 12 is wider vertically at its rear middle portion than at its ends.

In Figs. 4 to 7, inclusive, I have shown means for making the under surface 16 of the cap the shape or form desired. For this purpose I provide a jig 18 which consists of a bar of metal having a longitudinal slot 19 in its upper side for receiving one of the caps with its lower face 16 turned upwardly. The top surface 20 of the jig is flat except for cross bars 21 which are secured upon its two ends by screws 22. These cross bars are flat on their under surfaces and rest flat down upon the top surface 20 of the body of the jig, and consequently their undersides which span the slot 19 define the top of the slot 19. The ends 23 of the cap 5 are arranged beneath the cross bars 21 and the cap is forced tightly up against these cross bars by a screw 24 mounted at the middle of the length of the bar and under the rear part of the cap and the upper end of which is adapted to contact with the middle of the top of the cap 7.

In preparation for the step to be described the cap has been substantially finished, it has 45 been hardened and the bottom surface 16 of the cap 7 has been accurately ground and finished to a perfectly flat condition so that when the cap is placed in the jig, upside down, and the screw 24 is turned to set the ends of 50 the cap firmly against the under sides of end stops 21 the surface 16 of the cap lies flush and even with the top surface of the jig. Then the screw 24 is turned in a little more and this springs or curves the cap upwardly, 55 forcing its middle portion above its ends, as indicated by the full line in Fig. 5. It is obvious that this forcing of the middle portion upward above the top surface of the jig can be accurately determined by the pitch of the 60 thread of the screw 24 and the angle through which it is turned after the cap has been set firmly against the end bars 21. The amount of this lifting or bulging of the middle portion of the cup is indicated by the space between the solid line in Fig. 5 and the dotted

line 25, but in order to make a practical indication this is greatly exaggerated in the drawing, as in actual practice it is only between one and two thousandths of an inch. Having thus forced the middle portion of the cap above the flat top of the jig, the jig then is so set in relation to the grinding wheel that more of the excess or bulge is taken off at the rear edge than at the front edge, resulting in the crescent shaped surface shown shaded in Fig. 4.

This setting of the jig can be accomplished either by making the bottom of the jig on a slight incline or by laying a shim of the proper thickness under the front edge thereof in setting the jig in a grinding machine.

After the cap has been ground as described, it is released from the jig and it resumes natural condition. When released it naturally springs back to its original condition, and the rear middle portion having been removed by grinding the surface 16 of the mold surface of the cap is slightly curved from end to end. For the purpose of ease of manipulation the slot 19 in the jig 18 is made slightly wider than the extreme width of the cap and the cap is forced sidewise in the slot against one side wall by horizontal screws 26. These screws are tightened before the grinding step is begun so that the cap is held firmly during the grinding.

The base 8 is treated in a similar manner; in other words, it is also hollow ground. For this purpose a jig 27 is provided consisting of a block 28 cut away on one side to provide an upstanding wall 29 at one side with an inner flat vertical face 30 against which the base 8 is adapted to be firmly clamped by a centrally disposed screw 31 which fits in a suitable threaded opening provided in a centrally located boss 32. This boss constitutes the head of a bolt 33 which projects through the wall 29 and is clamped tightly in position by a nut 24 on its opposite end. The boss 32 serves as a support for the base 8, as the base is provided with an opening 35 in which the boss fits freely. The screw 31 holds the base tightly against the inner flat vertical face 30 of the wall 29 by means of a longitudinally arranged clamping bar 36 which bears at its end portions against the adjacent side of the base.

For springing the base 8 so that its middle portion can be ground off to make it hollow when released, I provide two pull-down screws 37, one at each end, each of which projects up through an opening in the base of the jig, the heads of the screws being shouldered in the base and their threaded upper ends engaging pull members 38, each of which has a horizontal projection 39 adapted to enter an opening in the base 8 near its end. It is now clear that when the base 8 has been clamped firmly in place by the screw 31 and is supported by the boss 32, the ends of the

base 8 can be drawn down by turning the screws 37 in the right direction. The dotted line 40 in Fig. 8 indicates the top of the base before it is sprung, and the full line indicates its top after it is curved. As before, this difference is very greatly exaggerated. Having sprung the base as described, the portion beyond the plate is ground off as before, and when the base is released it assumes its former conditions with this difference—that it is curved downwardly in its middle portion; in other words, it is slightly hollow ground from end to end. As with the cap, the jig is slightly tipped so that more is taken off the rear edge than the forward edge. Care is taken in each instance not to extend the grinding beyond the shaded area 16' shown in Fig. 12.

For guiding the cap in its relation to the base, rigid upstanding guide projections 41 are provided at the ends of the base 8, and the cap is provided with notches 42 at its end to receive these projections. But during the grinding operation on the base, these projections are removed, as indicated by the dotted lines in Fig. 8.

Having ground the cap and the base, the mold is assembled and the mold slot presented is wider at its rear middle portion than at its ends and is gradually tapered from its largest dimension of its center toward its ends and toward the front. Consequently, as the metal is forced into the mold slot in the usual process of casting slugs on a limo-type or similar machine, the casting will be thicker vertically of the slot at its rear middle portion than at its ends, but as the slug cools it will shrink vertically of the mold slot; that is, transversely of the slug to a greater extent at its rear middle portion than at its ends, and this shrinkage is exactly compensated for by the shape of the mold produced as described.

As many modifications of my invention will readily suggest themselves to one skilled in the art, I do not limit or confine my invention to the specific details of construction or steps of operation herein described.

I claim:

1. The herein described improvement in metal molds for producing hollow type furniture or base material having parallel side faces, which consists in making the mold slot wider at its rear middle portion than at its ends.

2. The herein described improvement in metal molds for producing hollow type furniture or base material having parallel side faces, which consists in widening the mold slot from both ends toward the middle and from its front side toward its rear side.

3. A metal mold for use in casting hollow type furniture or base material, said mold having a slot which is tapered in width from both ends towards the middle thereof and

from the front toward the rear, a longitudinal core in the mold slot, the widening of the slot being just sufficient so that the slugs when cast have parallel side faces.

4. A metal mold for use in casting type slugs for use as furniture or base material, the mold having a mold slot defined at one side by a cap and at the other by a base, means for spacing the cap and base apart, a core arranged in the slot for making the slugs hollow, both the cap and the base being hollow ground as described for the purpose specified.

5. A metal mold for use in casting hollow type slugs for use as furniture or base material, having parallel side faces, the mold having a slot in which the furniture is cast, the slot being slightly wider at its rear middle portion than at its ends, the two opposite faces of the mold defining its width being each inclined from its middle portion toward each end and from its rear face to its front face.

6. The herein described method of making caps and bases for printers' metal slug molds, which consists in first making the caps and bases substantially completely finished except their opposed faces, the parts having been previously hardened, then applying pressure to each part in such a manner as to force its face which is to be opposed to the other part to bulge at its middle rear portion, then grinding off such bulging portions whereby when said cap and base are released and assembled to form a mold the mold slot is wider at its middle rear portion than at its ends.

7. A metal mold for use in casting hollow type furniture, the mold having a slot which is wider at the middle portion of its rear side and which tapers toward the middle of the front edge and toward its ends.

8. A metal mold for use in casting hollow type furniture, defined at one side by a cap and at the opposite side by a base, the cap and base each being hollow ground at their rear edges, the grinding gradually lessening toward the front and disappearing at substantially the middle of the front edges of the two members and extending from the middle of the piece toward each end.

In testimony whereof, I have hereunto set my hand, this 18th day of September, 1928.

ASHTON G. STEVENSON. 120
